HIS ATTORNEY

UNITED STATES PATENT OFFICE.

TRACY R. GROVE, OF PORTLAND, OREGON.

GAME.

Application filed December 22, 1924. Serial No. 757,412.

To all whom it may concern:

Be it hereby known that I, TRACY R. GROVE, a citizen of the United States, and a resident of Portland, in the county of 5 Multnomah and State of Oregon, have invented a new and useful Game, of which the following is a specification.

This invention relates generally to the toy-making art, and particularly to that class of 10 games in which balls are driven about a plane surface under the direction of a cue.

The main object of this invention is to 15 produce a game which will provide an endless source of amusement and at the same time develop the skill of the player in proportion to the length of time it is played.

The second object is to provide a game 20 which can be played by two people, or can be played progressively.

25 These, and other objects, will become more apparent from the specification following as illustrated in the accompanying drawing, in which:—

Figure 1 is a plan of the game and Figure 2 is a longitudinal section taken along the line 2—2 in Figure 1.

Similar numbers of reference refer to the same parts throughout the views.

Referring in detail to the drawing, the 30 game itself consists of a flat base member 10, preferably of veneered board, and covered with a felt 11 resembling that used on billiard tables. Around the base 10 is placed a raised moulding 12, the inner side 35 of which is lined with strips of rubber 13 or other resilient material. Secured on the base 10 over the cloth 11 is a plurality of fences 14^A, 14^B, 14^C, 14^D, 14^E and 14^F which are provided with rounded ends 15 and 40 have the upper portion of their sides surrounded by rubber bands 16. A starting spot 17 is marked in front of the fence 14^D. Values ranging from five to twenty by fives are plainly marked with the characters 18, 45 18^A, 18^B, 18^C and 18^D.

A small ball 19, which may be taken as representing a rabbit, is of a size just capable of entering into the gateways 20 or passing through the openings 21. A large ball 50 22, representing a dog, and of a size too large to pass through the gateways 20 or openings 21, is also employed, as is a cue 23 of any convenient form.

The operation of the game is as follows:

The rabbit 19 is placed in the enclosure 55 marked with the character "5" which is indicated on the drawing at the same end of the game as is the character "10". The ball 19 may be placed in any of the three gateways 20 and shot through same by means of the 60 cue 23, the object being to get into one of the other compartments as soon as possible without exposing the ball 19 to the play of the ball 22. The ball 22 is now placed on the starting spot 17, and the opposing player, by means of the cue 23, attempts, by a banking shot as illustrated, for example, by means of the line 24, to touch the ball 19.

If the ball 22 strikes the ball 19 after 65 striking a cushion either on the moulding, or the fences, or both, the ball 19 is out of play and the two players exchange sides and the game is started over. If, however, the ball 19 succeeds in getting into any of the enclosures it is credited with the amount marked 70 thereon and the play proceeds alternately until the ball 22 finally touches the ball 19.

Following are the outstanding rules which 75 govern the game: A player cannot score twice in the same enclosure without first 80 having scored in one of the other enclosures. The large ball is placed in the circle in front of the end block on the opposite end of the board by player number two, his object being to strike the small ball by a cushion 85 shot. (A direct shot does not count.) If he should shoot it into one of the other enclosures, it is safe, and he adds the number of such enclosure to his score. If it is 90 shot through the opening between the side block and the side cushion, or between the end blocks and the end cushions, it is safe.

As soon as player number two succeeds 95 in hitting the small ball he takes it and the game proceeds as before, player number two playing the small ball first, and player number one trying to hit him with a cushion shot. Then they change again, the player winning who first gets a score of exactly fifty-five. If player number one 100 scores fifty-five first, player number two gets another chance with the small ball, his object being to tie the score. If he succeeds in doing this the game goes on until the tie is broken, the player getting the higher 105 score winning.

If the small ball enters an enclosure and rolls out without stopping, it does not score.

If the small ball hits the large ball, it loses, the same as if it had been hit by a large ball.

5 A ball is safe in an enclosure when a straight-edge placed across the corner does not touch it.

If the small ball is blocked in enclosure number ten, or in enclosure number twenty, it retains its score but goes to the shooter 10 of the large ball.

If the large ball jumps into an enclosure, or either ball jumps off the table, it is called no shot and the player has another try from the same position.

15 It will be understood that the exact construction of this board need not be followed. The balls 19 and 22 may be of any convenient material as long as they are limited in size, as suggested. The fences 20 also may vary from a wooden block covered with rubber, to a solid rubber block, or any variation thereof, without departing from the spirit of this invention. The side walls of the moulding may also be inclined 25 slightly after the fashion of a pool table in order to insure against the ball jumping over the side, as is commonly understood.

It will also be understood that in some 30 instances where it is not desirable to employ

a cue that a ring may be substituted for the balls and driven in the same manner in which carrom rings are played.

I am aware that many forms of games have been constructed in the past in which 35 balls are driven over a plane surface. I therefore do not claim such devices broadly, but I do intend to cover all such modifications as fall fairly within the appended 40 claim.

I claim:

A game board having, in combination, a flat rectangular base having a wall formed about the perimeter thereof, said wall having a resilient inner face, with a plurality 45 of fences mounted on said base within said wall, some of which fences forming narrow gated enclosures in the corner of said board, others forming a narrow gated enclosure in the center of said board, others forming 50 side barriers between the corner enclosures near the outer edges of said board, and others forming barriers between the center and outer closures; a small ball adapted to pass through any of said gateways; a large 55 ball incapable of passing through any of said gateways; a cue for driving both of said balls; and a resilient covering for said fences and barriers.

TRACY R. GROVE.
